UNITED STATES PATENT OFFICE

WILLIAM E. KEHOE, OF SAN FRANCISCO, CALIFORNIA

DESIGN FOR A COMBINATION BASE AND COLUMN FOR DISPLAY STAND

Application filed November 9, 1932. Serial No. 45,850. Term of patent 3½ years.

To all whom it may concern:

Be it known that I, WILLIAM E. KEHOE, a citizen of the United States, residing at the city and county of San Francisco, State of California, have invented a new, original, and ornamental Design for a Combination Base and Column for Display Stand, of which the following is a specification, reference being had to the accompanying drawing, forming part thereof, in which

The figure is a perspective view of a combination base and column for display stand.

I claim:

The ornamental design for a combination base and column for display stand, substantially as shown.

WILLIAM E. KEHOE.
